US00D635246S

(12) **United States Design Patent**
Striebig et al.(10) **Patent No.:** US D635,246 S
(45) **Date of Patent:** ** Mar. 29, 2011(54) **DOSE DISK FOR DRY POWDER INHALERS**(75) Inventors: **Rachel Striebig**, London (GB);
Matthew Allen, Swavesey (GB);
Thomas W. Ruckdeschel, Cary, NC
(US); **Charles Buckner**, Chapel Hill,
NC (US)(73) Assignee: **Oriel Therapeutics, Inc.**, Durham, NC
(US)(**) Term: **14 Years**(21) Appl. No.: **29/358,375**(22) Filed: **Mar. 26, 2010**(51) LOC (9) Cl. .... **24-01**(52) U.S. Cl. .... **D24/110**(58) **Field of Classification Search** D24/108-110.5,
D24/112-114, 181; 128/200.14-200.23,
128/203.12-203.24; D29/108

Primary Examiner — Ian Simmons*Assistant Examiner* — Charles D Hanson(74) *Attorney, Agent, or Firm* — Myers Bigel Sibley & Sajovec, P.A.(57) **CLAIM**

The ornamental design for a dose disk for a dry powder inhaler, as shown and described.

DESCRIPTION

FIG. 1 is a top perspective view of a dose disk for a dry powder inhaler showing our design;

FIG. 2 is a top view thereof;

FIG. 3 is a side view thereof;

FIG. 4 is an opposing side view thereof;

FIG. 5 is a bottom view thereof; and,

FIG. 6 is an end view thereof, the opposite view being the same.

The broken lines shown herein are for illustrative purposes only and form no part of the claimed design.
